UNITED STATES PATENT OFFICE

FOCSANEANU ALEXANDER, OF NEW YORK, N. Y., ASSIGNOR TO ARGCO TUBE AND TELEVISION CORPORATION, A CORPORATION OF DELAWARE

LIGHTING DEVICE

Application filed May 31, 1927. Serial No. 195,389.

The present invention relates to lighting devices of the type that comprises a glass tube or bulb containing an atmosphere of a conductive gas and electrodes enclosed within the tube.

Such tubes frequently contain one or more of the noble gases, such as neon, argon or helium, or mercury vapor, the gas being at relatively light pressures. When current is passed, the gas becomes ionized and there is a very considerable bombardment of the electrodes. If the electrodes are composed of iron, copper or nickel, as is usual, or of carbon, as is sometimes the case, a rapid disintegration of the electrode material takes place due to this bombardment. The material thus evaporated from the electrodes combines with the gas filling of the tube and is deposited in solid form on the glass walls with the result that the light is obscured and the gas becomes so depleted by combination with the evaporated material that in a comparatively short time the tube ceases to function.

In order to obviate this condition it has heretofore been the practice to form the electrodes in such manner that they might have a large superficial area. Careful experiment has resulted in the finding that the smallest superficial area that will give practical results in efficiency and life is 1.5 square decimeters per ampere. As the area of the surface increases above this figure, the heating effect due to the current is less and the evaporation correspondingly smaller.

Luminescent tubes having a relatively long life may indeed be made in this manner, for the very large superficial areas of the electrodes permit a cooling effect due to the amount of heat which is radiated from such large surfaces. However, as the radiated heat is confined within the narrow space of the electrode chamber, after a relatively short period of operation this advantage is lost and the confined heat of radiation serves once more to elevate the temperature of the electrodes and evaporation and depletion of the gas proceeds. In addition to this, electrodes of such large size are unsightly in appearance and present practical difficulties in the manufacture of the tubes.

It is an object of the present invention to provide a luminescent tube which will operate with great efficiency during a long useful life and which will avoid the defects above mentioned. It is a further object to provide an electrode for such tubes having a superficial area substantially less than 1.5 square decimeters per ampere. It is a still further object to provide means for cooling such electrodes by carrying away the heat from the same and radiating it outside the electrode chamber and outside the tube.

Other objects and advantages will appear from a consideration of the forms of the device illustrated in the drawings to which reference is now made.

Fig. 1 is a view in elevation of a luminescent tube embodying the invention.

Fig. 2 is a longitudinal section through one end of said tube.

Fig. 3 is a view in perspective of the electrode and heat radiating structure of said tube.

Referring to Fig. 1, 1 indicates the tube which may be of any suitable form or dimensions. Into the ends of the tube, 1, are sealed the heat dissipating elements, 2, which carry the electrodes, 3. At the outer end of the heat dissipating element 2, which consists, preferably, of a cylinder of copper of relatively large size with respect to the electrode, 3. Connection is made with a source of electric current not shown by the conductors, 4. The electrode, 3, may be of iron, aluminum, copper or other suitable metal. It may be of any suitable size above or below 1.5 square decimeters per ampere and is mounted in a cup, 5, formed by the hollowed out inner end of the heat dissipating element, 2. The rim, 6, of the cup, 5, is made very thin to facilitate the formation of a seal with the glass of the tube, 1, in the manner hereinafter described.

The electrodes, 3, if formed of a metal different from that of the heat dissipating element, 2, is set into a hole, 7, as indicated in Fig. 2, and may be fixed there by a welding, soldering, riveting, or, by a thread, or otherwise. A sufficient area of the surface of the electrode is thus in intimate contact with the heat dissipating element, to impart its heat

thereto and permit of its being carried away and radiated into the air through that portion of the element which is external to the tube. If on the other hand the heat dissipating element and the electrode are of the same metal, they may be turned out of single piece and embodied in one structure. It will be evident that the heat dissipating element, 2, performs the function of leading current to the electrode, 3, in addition to that of carrying the heat away therefrom and radiating it outside the tube. For this reason, I prefer to form the heat dissipating element of a metal of superior electrical and thermal conductivity such as copper. Furthermore I may protect this element, 2, by a casing or guard, 8, made of a material which is a poor conductor of electricity, as for example glass or hard rubber, provided with perforations to facilitate the escape of the heat of radiation. This is desirable in some cases to avoid accidental shocks but not on account of the heat of the element, for even during long operation the heat dissipating element remains sufficiently cool to enable one to touch it without being burned.

In Fig. 3, the heat dissipating element is shown in perspective so as to display the cup into which the electrode is set. The element 30 is turned out of a single piece, preferably of copper for the reasons above set forth, and one end is hollowed out to form a depression, 5, with a rim, 6, of very great thinness, of the order of .005 to .010 inch. In the center of 35 the floor, 5, of this depression or cup, is the hole, 7, bored to accommodate the electrode, 3, of Fig. 2.

After the electrode, 3, has been mounted in the hole, 7, the heat dissipating element, 2, is 40 sealed to the glass tube, 1, in the following manner. It is well known that fused glass will easily "wet" copper, but that on cooling the copper will draw away from the glass because of the difference in coefficient of expansion. If, however, the edge of the copper be 45 made of the order of thinness above mentioned, from .005 to .010 inch, when the end of the glass tube is softened by heat and the thin rim, 6, also heated is pushed into it and held 50 there until cooling, a good airtight seal is made.

When the seals are formed in this manner at both ends of the tube, the air is evacuated in a known manner, and the conductive gas 55 is introduced. The nature of the gas and the pressure thereof will be determined by the use to which the device is to be put and by other considerations. If the gas be neon, for example, the pressure may be increased to obtain a brilliant red light or diminished to obtain a more orange color, varying perhaps from 15 mm. of mercury to 5 mm. of mercury.

By the practice of the present invention an efficient tube of long life is obtained which 60 is remarkable for its brilliancy and the main-

tenance of the constancy of its color throughout its life.

Having thus described my invention what I claim is:—

In a neon tube and the like, the combination of a small diametered glass tube suitable for forming a letter and the like in an illuminated sign; electrodes therefor at the open ends of said tube, the electrode construction comprising a heat-radiating metallic body 70 external to the tube adjacent an end thereof with its face closing the mouth of the tube, said metallic body at said face being formed with a thin walled annular flange surrounding and sealed to the wall of the tube; and said metallic body further being provided at said face with a metallic projection forming the actual electrode projecting axially into the tube; and a cap of electrically non-conductive material enclosing said metallic body, said cap being interiorly larger than said body so as to be air-spaced therefrom and being perforated for circulation of atmospheric air to and from the metallic body. 80

In witness whereof, I have hereunto subscribed my name this 19th day of May, 1927.

FOCSANEANU ALEXANDER.
